CAMERA DOLLY

John D. McCollough, Los Angeles, Calif.

Application December 28, 1953, Serial No. 28,227

Term of patent 14 years

(Cl. D61—1)

Fig. 1

Fig. 2

Fig. 3

Fig. 4

To all whom it may concern:

Be it known that I, John D. McCollough, have invented a new, original, and ornamental Design for Camera Dolly, of which the following is a specification, reference being had to the accompanying drawing, forming a part hereof.

Fig. 1 is a rear perspective view of a camera dolly showing my new design;

Fig. 2 is a front end elevational view thereof;

Fig. 3 is a side elevational view thereof;

Fig. 4 is a top plan view thereof.

I claim:

The ornamental design for a camera dolly, as shown.
